UNITED STATES PATENT OFFICE

JAMES H. RAND, JR., OF BUFFALO, NEW YORK, ASSIGNOR, BY MESNE ASSIGNMENTS,
TO REMINGTON RAND INC., OF NEW YORK, N. Y., A CORPORATION OF DELAWARE

CARD INDEX OR RECORD DEVICE

Application filed November 6, 1926. Serial No. 146,625.

This invention relates to improvements in card indexes or record devices of that kind in which a plurality of cards, card holders or record-bearing members are arranged in overlapping, nested arrangement so that a portion of each holder or device is exposed beyond the adjacent cards or members.

These cards or card holders usually comprise a body portion formed of a flat sheet of suitable material, along one edge or edge portion of which a flat strip is secured, so as to lie against the body portion and provide a flap. The body portion and flap are adapted to be spread apart slightly to permit the insertion of corresponding edges of another card or record-bearing member, whereby a series of the cards may be interlocked and held in overlapping, nested arrangement.

In practice, a series of such nested, overlapping cards or card holders are supported on a tray or slide, and the individual card holders are provided with opposite lateral extensions or lugs adapted to be inserted beneath spaced, overhanging flanges of the side walls of the tray to permit longitudinal movements of the series of cards on the tray while preventing lateral movements thereof, and to permit the nested cards or holders to be separated either singly or in groups for insertion and removal into and out of the tray.

For so inserting or removing the record devices, they must be bent or flexed between their side edges to permit the insertion of the lugs beneath the overhanging flanges of the tray.

One of the objects of the present invention is to construct a card index or record device provided with a card, card holder or record-bearing member having a flap or attaching member of improved construction adapted to facilitate the guiding of the cards or holders into interlocking, nesting relation; also to provide a card, card holder or record-bearing member having a flap formed of relatively stiff material adapted to strengthen the card or holder and increase the life thereof, said flap being formed so that the card can nevertheless be easily flexed for insertion into or removal from the supporting tray or slide,

and this without injuring or reducing the guiding and nesting qualities of the flap.

Another object of the invention is to provide a card index or record device having a tray or slide for supporting a series of such card holders arranged in overlapping, nested relation, and which is provided with means whereby the flaps of the several card holders will be protected and be prevented from flattening out in use; also to provide a card, card holder or record-bearing member, and a tray or support therefor, each having cooperating parts whereby the several cards or card holders will be properly aligned and prevented from lateral displacement on the tray and at the same time permit easy sliding movements of the cards on the tray, said parts on said tray being further adapted to relieve pressure on the flaps in the use of the record devices; and also to improve record devices of the kind mentioned in the other respects hereinafter specified and claimed.

In the accompanying drawings,

Fig. 1 is a plan view of a record device embodying the invention, comprising a tray or slide and a plurality of overlapping, nested cards, card holders or record-bearing members.

Fig. 2 is a fragmentary, sectional view of a portion of one of the improved cards or card holders.

Fig. 3 is a fragmentary, longitudinal section on an enlarged scale, on line 3-3, Fig. 1, of a portion of the tray or slide and a plurality of the cards or card holders arranged thereon in overlapping, nested relation.

Fig. 4 is a transverse section of the tray on line 4-4, Fig. 1 on an enlarged scale, and showing one of the cards or card holders flexed for insertion into the tray.

Fig. 5 is a similar figure showing the card or card holder in operative position in the tray.

Fig. 6 is a fragmentary face view of the front of one of the cards or card holders.

Fig. 7 is a similar view showing the top portion of the rear of the card with the improved flap secured thereto.

Fig. 8 is a top plan view of a portion of the tray and the flap or attaching portion of

the card, showing the relation of the cooperating parts of the tray and flap.

The card index or record device shown in the drawings includes a plurality of record-bearing cards or members 10 each having a body portion 11 formed of a sheet of suitable material on which the records or other matter may be inscribed directly, or the member may be provided with a sheath or pocket at 10 the lower edge thereof as shown at 12, Fig. 1 and 6, into which an edge of a record-bearing card may be inserted. Each member 10 is further provided with a flap 13, in the form of a strip 13a of material secured face-to-face along the upper edge of the body portion 11, as by staples or wire stitches 14, or otherwise. The staples 14 are disposed so that the flap lies on the back of the member and is free to be flexed or spread at its inner edge away from the body member so as to form a narrow wedge-shaped space into which the top of another record member can be inserted and positioned adjacent the staples 14, and be frictionally held in position 20 25 so as to nest therein with its lower edge exposed beneath the lower edge of the first member. A plurality of the card members, when nested in overlapping relation, are placed in a tray 15, having a bottom wall 16, opposite side walls 17 for preventing lateral displacement of the cards or members 10, said walls being provided with flanges 18 overhanging the bottom 16, and beneath which laterally extending lugs 19, formed on 30 35 the strips 13a are adapted to be inserted to maintain the members in their sliding movements lengthwise of the tray. The body portions 11 of the card members are substantially as wide as the space between the flanges 18, and the members are detachably secured on 40 45 the tray by flexing them between their side edges so as to engage the lugs 19 beneath said flanges. A series of the members 10 are releasably held in their nested arrangement and prevented from unintentional lengthwise 50 55 movements on the tray by a suitable movable compressor or follower 20 at one end of the tray and which engages between the body and flap of the adjacent end card member to press the series towards a stationary stop or wall 21 at the opposite end of the tray. The parts thus far described are of known construction and except as hereinafter set forth, form no part of the present invention.

55 In card holders or members as previously constructed, the flaps, as well as the body portions thereof, have been formed of flat pieces of material, so that the flap engaged or contacted with the body portion throughout substantially the whole area of the flap, with the result that it has been found difficult to insert the edges of the cards between the flaps and body portions for nesting them.

In order to facilitate the insertion of the 60 upper edges of one card member beneath the

flap of another card member, the flap 13, in accordance with this invention is specially formed so as to provide a space between the free edge of the flap and the card body. In the particular arrangement shown in the drawings for this purpose, each flap 13 is scored or creased a short distance from and parallel to its free edge 23, as at 24 along which the flap is bent so as to provide an edge portion 25 which flares or extends outwardly 70 or rearwardly at an angle to the body portion of the card holder, thus forming a space 26 (see Fig. 2) into which the edge of another card holder can be easily inserted so as to guide it to nesting position as shown in Fig. 3. 75 80

If the flared edge 25 were made continuous from end to end of the flap 13, this edge portion would buckle and be eventually broken by the flexing of the card holder in the insertion and removal thereof into and out of the tray, and the presence of the angularly extending portion 25 would stiffen the flap and resist or interfere with the easy flexing of the card holder. To avoid this objection the edge portion 25 is cut away intermediate of its ends, thus forming a recess 28, and providing a reduced flat portion 29 in the flap which will permit the card holder to be easily flexed without buckling or otherwise affecting the two separate parts of the flared edge 25, see Fig. 4, by bending the card and flap transversely across said reduced portion 29. The outer ends of the edge 25 are also cut away to form the lugs 19, which are thus made flat and will not be readily broken or 95 100 deformed in use.

The bottom walls, in trays heretofore provided, have usually been made entirely flat. The use of a flat-bottomed tray, however, with cards or holders having their flaps or attaching members formed as above described, would be objectionable, as the portions of the flared edge 25 would, by engaging the continuous flat bottom, be flattened out, as by the pressure exerted on the card series by the hand of the user when making entries in the index, or in other ways, thus destroying the usefulness of the improved flaps for the purpose stated. In order to overcome this difficulty, and protect the flared edges 25 of the card holders and relieve them from pressure and undue wear in use, the tray 10, in accordance with the invention is specially constructed so as to provide parts cooperating with the cards or holders to effect such results. The means shown comprise spaced raised portions 30 extending longitudinally at opposite sides of the bottom wall 16 and an intermediate raised portion 31, thereby forming spaced depressions 32 extending from front to rear of the tray and alternately with the raised portions 30, 31. The side portions 30 are disposed so as to extend beneath and support the side guide lugs 19 of the flaps, while the intermediate portion 31 110 115 120 125 130

extends into the cut-out spaces 28 between the separate portions of the edges 25 and extends beneath and in contact with the flat reduced portions 29 of the flaps. By this arrangement the main portion of the flaps 13, by their connection with the flat bodies 11 of the cards or holders 10, are maintained in substantially horizontal position when nested in series so as to extend across and be substantially flat upon the raised portions 30 and 31, while the portions of the flared edges 25 extend downwardly into the depressions 32 adjacent the face of the bottom wall 16. The pressure of the hand of a person writing on the index is usually substantially midway between the side edges of the tray, so that this pressure is largely exerted upon the parts 29 of the flaps and the raised portion 31 of the tray, so that the nested cards will not be normally flexed or buckled to an extent that will cause the straightening out of the edge portions 25 in the recesses 32. The cut-out portions of the flap 13 are of substantially the same width as the width of the raised portions 30, 31 of the tray, so that these portions 30, 31 act to cooperate with and guide the cards or holders longitudinally of the tray and maintain the series in alinement.

If desired, the flaps 13 may be provided with spaced cut-out tongues or parts 35 adapted to extend upon the front faces of the card bodies to stiffen or reinforce the cards and prevent their upper edge portions from being crumpled or torn in use. The card bodies are, as usual, provided with scoring or perforations 36 to permit them to be turned back to give access to underlying cards, or for inserting matter on the backs of the cards or holders.

By forming the cards or card holders and the tray as described, an improved record device is provided which is more practical than such devices heretofore known, and greater efficiency in use is ensured by the ease with which the cards may be nested. The life of the cards is also increased by the protecting means outlined to an extent which greatly offsets the slight increase in cost of production due to the extra operations involved.

I claim as my invention:

1. An index or record card, having a body member for receiving record matter and a flap secured at one edge of said body member and having a free part adapted to lie flat against said body member and between which and said body member an edge of another card may be inserted and frictionally held, whereby a plurality of said cards can be arranged in overlapping, nested relation, said free part having an edge portion extending outwardly in angular relation thereto and to said body member to facilitate the insertion of another card beneath said flap.

2. A card index or record device comprising

ing a tray or slide, a series of cards arranged in overlapping, nested relation in said tray, each of said cards having a flap extending along one edge and beneath which an edge of another card may be inserted for nesting said cards, said flap comprising a flat portion extending substantially parallel with said card for engaging and frictionally holding said other card, and an outwardly deflected edge portion adapted to facilitate the insertion of said card beneath said flap.

3. A card index or record device comprising a tray or slide, a series of cards arranged in overlapping, nested relation in said tray, each of said cards having a flap extending along one edge and beneath which an edge of another card may be inserted for nesting said cards, said flap comprising a flat portion extending substantially parallel with said card for engaging and frictionally holding said other card, and an outwardly deflected edge portion adapted to facilitate the insertion of said card beneath said flap, said tray having a bottom wall on which said card series are supported, and opposite side portions, said cards having opposite lateral lugs adapted to extend beneath said tray side portions for releasably holding said series on said tray, and said outwardly deflected edge portions of said flaps being cut away between their ends to allow said cards to be flexed for inserting said lugs beneath said tray side portions without deforming said edge portions.

4. A card index or record device comprising a tray or slide, a series of cards arranged in overlapping, nested relation in said tray, each of said cards having a flap extending along one edge and beneath which an edge of another card may be inserted for nesting said cards, said flap comprising a flat portion extending substantially parallel with said card for engaging and frictionally holding said other card, and an outwardly deflected edge portion adapted to facilitate the insertion of said card beneath said flap, said edge portion being cut away at opposite ends of said flap and also intermediate thereof, said tray having spaced longitudinally disposed raised parts adapted to extend into the cut-out portions of said flap to support said cards and flaps flatwise on the tray and permit the remaining parts of said edge portions to extend between said spaced tray parts substantially out of contact with said tray.

5. A card index or record device comprising a tray or slide, a series of cards arranged in overlapping, nested relation in said tray, each of said cards having a flap extending along one edge and beneath which an edge of another card may be inserted for nesting said cards, said flap comprising a flat portion extending substantially parallel with said card for engaging and frictionally holding said other card, and an outwardly deflected edge portion adapted to facilitate

- the insertion of said card beneath said flap, said edge portion being cut away at opposite ends of said flap, and also at an intermediate portion thereof, said tray having a bottom wall formed with spaced longitudinally disposed raised parts alternating with depressed parts, said raised parts thereof being adapted to extend into the cut-out portions of said flap to support said cards and flaps flatwise on the tray, and the remaining parts of said flap edge portions being adapted to extend into said depressed parts of said tray bottom, whereby they are protected in the use of the record device.
6. A card index or record device comprising a tray or slide, a series of cards arranged in overlapping, nested relation in said tray, each of said cards having a flap extending along one edge and beneath which an edge of another card may be inserted for nesting said cards, said flap comprising a flat portion extending substantially parallel with said card for engaging and frictionally holding said other card, and an outwardly deflected edge portion adapted to facilitate the insertion of said card beneath said flap, said edge portion being cut away at opposite ends of said flap to form laterally extending flat lugs, and being also cut away at a portion intermediate of its ends, said tray having longitudinally disposed raised side parts extending beneath said lugs and overhanging parts depending adjacent said lugs, and said tray also having an intermediate, longitudinal, raised part adapted to extend into the intermediate cut-out portions of said flaps and which together with said side parts support said cards and flaps crosswise of the tray, and permit the remaining parts of said flap edge portions to extend between said raised tray parts, and the intermediate cut-out portions of said flaps being adapted to permit said cards to flex between their ends for inserting said lugs beneath the overhanging parts of said tray.
7. In an index or file, a tray having a bottom generally flat and horizontally disposed, upwardly extending portions forming side walls, and inwardly and downwardly extending portions from the upper edges of the side walls terminating in spaced parallel relation to said bottom, said bottom having the marginal portions at opposite sides and an intermediate longitudinal portion offset upwardly to support cards in said tray substantially flat and permitting depending flaps to extend between said offset portions of said bottom.

JAMES H. RAND, JR.
